(Cl. D26—5)

Fig. 1.

Fig. 2.

Fig. 1 is a perspective view of an electronic cabinet showing my new design; and Fig. 2 is a side elevational view thereof. The opposite side, not shown, has substantially the same appearance as the side shown and the back is conventional.

The dominant features of my new design are shown in solid lines in the drawing.

This application is a division of my co-pending design application Serial No. D. 27,106, filed on October 7, 1953 now Patent Number D. 180,307, granted May 14, 1957.

I claim:

The ornamental design for an electronic cabinet, substantially as shown and described.
